UNITED STATES PATENT OFFICE.

LEE STURGES, OF ELMHURST, ILLINOIS.

DESIGN FOR A BICYCLE-FRAME.

SPECIFICATION forming part of Design No. 25,999, dated September 8, 1896.

Application filed May 16, 1896. Serial No. 591,886. Term of patent 7 years.

To all whom it may concern:

Be it known that I, LEE STURGES, a citizen of the United States, and a resident of Elmhurst, in the county of Du Page and State of Illinois, have invented and produced a new and original Design for Bicycle-Frames, of which the following is a specification, reference being had to the accompanying drawing, which shows a perspective view of the frame as a whole.

The distinctive feature of my design consists in the peculiar shape and configuration of certain raised portions which surround or surmount the frame-bars at the several joints of the frame, to wit: at the head, the front forks, the crank-hanger, and seat-post. At the juncture of the head A with the upper frame-bar A' are raised portions a, which extend from the head A rearwardly along said bar on opposite sides thereof and terminate in rounded tapering points. Similar raised portions a' extend from the head rearwardly along the lower frame-bar A² and have similar pointed terminals. Both the raised portions a and a' are flush with the head A, and a smooth continuous surface is presented from the point of the upper portions a around down the head to the points of the lower portion a'. At the crank-hanger A³ raised portions a² a³ and a³ a³ extend from the crank-hanger along the lower frame-bar A² and upright A⁴ and terminate in rounded tapering points. These raised portions a² and a³ are flush with and merge into each other at and

around the crank-hanger, and, as seen in side elevation, present a bifurcated appearance along the lower end of said bars A² and A⁴. Similar bifurcated raised portions a⁴ extend rearwardly along the lower rear fork-bars past the cross-brace A⁶. The ends of the frame-bars A' and A⁴, near the seat-post C, are provided with lateral raised portions a⁵ and a⁶, which round into and are flush with each other and which terminate in somewhat bluntly-pointed ends, like the raised portions 45 at the other joints of the frame.

The front forks B are provided at their upper ends with raised portions b and b', which extend downwardly along the front and rear edges of the forks. At the upper end of the latter, just beneath the fork-crown B², said raised portions b and b' merge into each other and completely surround the fork-bar. At their lower ends said raised portions taper to blunt points and the raised portions b are 55 made considerably longer than the raised portions b'.

I claim as my invention—

The design for a bicycle-frame, substantially as shown and described. 60

In testimony that I claim the foregoing as my invention I affix my signature, in the presence of two witnesses, this 13th day of May, A. D. 1896.

LEE STURGES.
